EXPLOSIVE DUMP SHELL

Paul F. Lewis, Tulsa, Okla., assignor to E. I. du Pont de Nemours & Company, Wilmington, Del., a corporation of Delaware

Application April 26, 1948, Serial No. 23,303

4 Claims. (Cl. 102—22)

1

This invention relates to an improved shell for dumping materials such as explosive charges in bore holes and the like, and more particularly, to a dump shell having increased loading ease, increased dumping ease, and increased capacity over prior art dump shells of equal dimensions.

U. S. Patent 2,384,534, dated September 11, 1945, granted to Oscar E. Chenoweth and myself, disclosed a dump shell for dumping explosive charges having a flexibly linked combination of elements inseparably secured together for operative purposes so as to prevent leakage and the loss of parts, and which at the same time permitted charging, discharging and recharging the shells readily and with a minimum of difficulty.

While the dump shell described therein constituted a considerable improvement over the prior art devices, it had an inherent disadvantage in that the end closure supporting member or cable extending through the vertical axis of the shell acted as an obstruction to filling the shell with cartridges of conventional size and thus limited the capacity of the dump shell, and also limited the size of the individual charges. In addition, the permanently attached ball-closure means tended to interfere with the free passage of the explosive charge at the point or elevation where charge was intended to be dumped so that a portion of the contents of the shell would be dumped after the shell had been raised above the stratum to be shot. Obviously, this latter occurrence created a dangerous situation as it resulted in premature explosions.

In addition, when this ball closure shell was raised after dumping, usually at high speed, the ball remained suspended below the body of the shell. In that position, in passing through well fluids it was whipped against the well bore and thereby damaged resulting in leakiness and the need for frequent replacement.

It is, therefore, an object of the present invention to provide a safer, more economical dump shell which will release its contents where desired with greater certainty. A further object of the present invention is to provide a dump shell having increased capacity per unit of shell volume. A still further object of the present invention is to provide a dump shell having greater ease of loading. A further object of the present invention is to provide a dump shell particularly suited for depositing explosive charges in bore holes. Additional objects will become apparent as this invention is further described.

These objects are accomplished by the following invention, one embodiment of which is illus-

2

trated in the accompanying drawings in which Figure 1 is a view showing the loaded shell being lowered in a vertical bore hole; Figure 2 is a view of the same shell after the bottom of the bore hole has been reached and the shell partially raised again; Figure 3 is an enlargement of the end closure element in the engaged position; Figure 4 is a view of the positions of the releasing mechanism with the yoke at a lower suspension point; and Figure 5 is a view of the latch jack used in the illustrated embodiment of the invention.

In the drawing, 1 is the shell or casing for holding the explosive charge; 2 is the closure element at the discharge end of the shell 1; 3 is a bail or bracket attached to the upper end of the shell 1; 4 is a support for the yoke assembly consisting of the yoke 5, spindles 6, spindle guides 7, and springs 8. Flexible stranded wire airplane tiller rope members 9 connect the latch jacks 10 to the yoke 5. The latch jacks 10 are adapted to fit in the recesses 11 of closure element 2, and are retained in that position by the shoe ring 12 when the yoke is at an upper suspension point. 25 The yoke assembly is releasably held at an upper suspension point by the hook 13, which is pivotally connected to the chain swivel 14, the lowering cable (not shown) being also connected to the swivel 14. 15 is the well wall, 16 the explosive charge, and 17 is the drop link attached to the yoke 5.

In operation, the embodiment illustrated herein is used in the following manner. The shell assembly is suspended on the lowering cable with the drop link 17 disengaged from the hook 13. The release mechanism is then pulled downward to the position shown in Figure 4, and the closure element 2 is placed in position so that the latch jacks 10 are engaged with the recesses 35 11. The latch jacks 10 are held in place while the springs 8 are allowed to raise the assembly. The hook 13 is then engaged with the drop link 17, and the desired amount of explosive 16 is loaded into the shell 1 at the upper end of the shell. After loading, the shell is lowered into the bore hole 15, until it reaches the bottom, as will be indicated by change in tension on the lowering cable and by meter readings. By slackening the lowering cable sufficiently, the hook 13 descends, thereby pushing drop link 17 out of the notch into the position shown in Figure 2. When tension is restored on the lowering cable, the weight of the charge 16 overcomes the tension of springs 8, thereby causing the latch jacks 40 10 to extend below the shoe ring 12. the inward pressure of the shoe ring, the latch jacks spread, allowing the closure element to be detached. The springs 8 draw the yoke assembly to the upper suspension point drawing latch jacks 10 into the shell and protecting them from damage in ascent, and as the shell assembly is raised, the explosive charge 16 remains on the bottom of the bore hole or at any desired stratum level in the well.

It is obvious that the number of flexible members may be greater than 2, or that the spindles and spindle guides may be replaced with other guiding means, or that an equivalent system may be substituted for the illustrated spring suspension, or the release mechanism may be altered, etc. The drawings, therefore, are illustrative of only one embodiment of the present invention, and the invention is not to be understood as limited to the particular embodiment shown.

This dump shell is adapted for use in all types of vertical bore holes and many types of materials, but is particularly applicable for dumping explosives in oil wells. The explosive charge used may be any of the explosive compositions known to the art of oil, gas, water well, submarine or other types of sub-surface shooting. The closure element may be machined to a leak proof fit, or provided with gaskets if liquid or semi-liquid materials are to be used. Where metallic debris in the bore hole is objectionable, the closure element may be made of some frangible non-metallic material such as glass, Bakelite, plastics, resins, etc. Similarly, the flexible members connecting the yoke and the latch jacks need not be any particular type of fibre or wire rope or cable, any type of linkage of suitable tensile strength being suitable.

It will be seen from the forms illustrated by the drawings that the improved closure means operates readily and quickly to permit easy charging and discharging, and at the same time forms a snug, safe closure for the shell. There is no chance for solid materials to become wedged between the end closure and the shell or the well bore, and thereby be partially raised before becoming dislodged. By the elimination of a central flexible member, the charge carrying portion of the shell is freed of an obstruction which prevented loading of the shell body to full capacity.

From the foregoing, it will be apparent that I have provided a dump shell which is adapted for wide usage in this art with a higher degree of safety, and which, when lowered into a well,

releases its charge of material positively and without the disadvantages of prior devices intended for similar purposes.

Having thus described this invention, I intend that my invention be limited only according to the following patent claims.

I claim:

1. A dump shell for depositing explosive charges at the bottom of a vertical bore hole by means of a lowering cable under tension comprising a shell or casing for containing the explosive charge, a fully detachable closure element containing latch jack recesses for the discharge end of said shell, and tension-responsive mechanism mounted in a bail attached to the upper end of said shell, said tension-responsive mechanism comprising a hook pivotally connected to the lowering cable, a drop link adapted to be releasably engaged by said hook, a yoke secured to said drop link, yoke guiding means attached to the inside of said shell, a plurality of separated flexible members suspended from said yoke adjacent to the inner periphery of said shell, said members terminating in latch jacks adapted to engage said closure element, whereby said closure element is held in position by the wedging of the latch jacks into the latch jack recesses in said element by the lower end of the shell while the yoke is at an upper suspension point.
2. A dump shell as claimed in claim 1, wherein spring suspension means are interposed between the yoke guiding means and the yoke, said spring suspension means having sufficient strength to support only the yoke, the flexible members and the closure element.
3. A dump shell as claimed in claim 1, wherein the flexible members are made of steel airplane tiller rope.
4. A dump shell as claimed in claim 1, wherein two flexible members are used.

PAUL F. LEWIS.
